UNITED STATES PATENT OFFICE.

FREDERICK WAGNER, OF NEW YORK, N. Y., ASSIGNOR TO NILES-BEMENT-POND COMPANY, OF JERSEY CITY, NEW JERSEY.

GAPPED WHEEL.

No. 923,467.

Specification of Letters Patent.

Patented June 1, 1909.

Application filed December 28, 1908. Serial No. 469,698.

To all whom it may concern:

Be it known that I, FREDERICK WAGNER, a citizen of the United States, residing at Mott Haven, New York, New York county, New York, have invented certain new and useful Improvements in Gapped Wheels, of which the following is a specification.

It frequently happens that gear wheels and other wheels require to be radially gapped to admit an axle or shaft, a patch-block being employed to close the gap at the periphery of the wheel. As an example of the use of such wheels, there is in common use a type of lathes for turning car wheels while on their axles, the lathe-arbor being a tubular affair encircling the axle between the wheels and having a face-plate on each end. The arbor is turned by a gear-wheel formed with or secured to it, and, in order that the axles may be gotten into the arbor, it is necessary to radially slot the arbor and the gear-wheel and to provide a separable patch for the gap at the periphery of the gear-wheel.

My invention pertains to an improved system for patching the periphery of a gear or other wheel at its gap, and I illustrate the invention as applied to a gapped gear-wheel on the arbor of a lathe of the class above referred to.

My improvements will be readily understood from the following description taken in connection with the accompanying drawing in which:

Figure 1 is a face elevation of a gapped gear embodying my improvement, the arbor with which the gear is connected appearing in vertical transverse section in the plane of line *b* of Fig. 2. Fig. 2 a horizontal section of the gear in the plane of line *a* of Figs. 1, 3, 4, 5 and 6: Fig. 3 a vertical transverse section of the gear in diverse planes indicated by line *c*, *c*, of Fig. 1: Fig. 4 an elevation of the inside face of the patch-block: Fig. 5 a vertical section of the patch-block and its seat in the plane of line *d* of Figs. 2, 3, and 4: Fig. 6 an edge elevation of the gapped and patched rim of the wheel: and Fig. 7 a similar view illustrating a wheel having its gap and patch arranged in planes non-parallel with the axis of the wheel.

A diversity of scales is involved in the drawing.

In the drawing, ignoring Fig. 7 for the

present:—1 indicates the wheel: 2, its radial gap: 3, the arbor with which the wheel is connected: 4, the face-plates on the ends of the arbor: 5, the teeth with which the wheel is provided in case it is a gear-wheel, as is the case in the example illustrated: 6, the patch-block fitted to slide transversely in the gap at the periphery of the wheel, the patch fitting its guideway closely: 7, an outwardly presenting shoulder on each wall of the gap at the seat of the patch-block: 8, an inward projection from the patch-block at one side of the web of the wheel, this projection being flanged to engage suitable guideways on the inner face of the wheel-rim: 9, an inwardly open recess in the patch-block-projection 8: 10, dowel-pins mounted in the opposite walls of the recess and adapted for movement into and out of dowel-holes in the walls of the gap: 11, springs connected with the dowel-pins and urging them outwardly into the dowel-holes: 12, an inwardly projecting handle secured to each dowel-pin: and 13, screws in the patch-block-projection, engaging keyways in the dowel-pins to keep the dowel-pins from turning.

The patch-block proper is the full width of the rim of the wheel while its inward projection 8 may well be restricted in width so as to lie entirely at one side of the web of the wheel, or at one side of the arms of the wheel if the wheel be of arched type. To remove the patch-block the handles are compressed toward each other and the patch withdrawn sidewise from the wheel, the patch being inserted in the gap by an opposite manipulation. The fitting of the patch in its seat in the gap is such as to insure the proper relationship of the patch-block to the walls of the gap, the main object of the dowel-pins being to hold the patch in place in the wheel rather than to position the patch radially in the wheel. One dowel-pin alone will answer this purpose, but I prefer a pair of them as illustrated and, whether one or two dowel-pins be employed, it is decidedly advantageous to provide the patch with a pair of handles, in order that the grasp of the hand may be readily effective in drawing inward the one or two dowel-pins which may be employed.

In the use of this patch system of gapped-wheel it is advisable to fit and place the patch before the rim of the wheel is finished,

regardless of whether the wheel-rim be plain or toothed. For instance, in a toothed wheel with cut teeth, the teeth should be cut in wheel and patch after the patching is completed.

Under ordinary circumstances the patch may slide into the gap in a path parallel with the axis of the wheel but in some cases gear-wheels have their teeth at an angle to the axis of the wheel, as in the case of worm-gears and angle-gears and, in such case it is advisable that the guideway for the patch be arranged at an angle corresponding with that of the teeth. Thus Fig. 7 illustrates a wheel with its patch at an angle to instead of parallel with the wheel-axis, and the angle for the seating of the patch should correspond, substantially, with the angle at which the teeth are formed. I may add that in lathes of the type above referred to it is common to drive their arbors by means of gear-wheels having their teeth disposed angularly and acting as worm-gears.

I claim:

1. A gapped wheel comprising, a wheel having a radial gap provided with a transverse guideway at the periphery of the wheel, a patch fitted to slide in said guideway, a dowel-pin projecting from said patch to a wall of the guideway and adapted to enter a dowel-hole in such wall, a spring co-operating with said dowel-pin and serving to seat it in its dowel-hole, and an inwardly projecting handle connected with the dowel-pin, substantially as set forth.

2. A gapped wheel comprising, a wheel having a radial gap provided with a transverse guideway at the periphery of the wheel, a patch fitted to slide in said guideway, a dowel-pin projecting from said patch to a wall of the guideway and adapted to enter a dowel-hole in such wall, a spring co-operating with said dowel-pin and serving to seat it in its dowel-hole, an inwardly projecting handle connected with the dowel-pin, and a second handle projecting inwardly from the patch and adapted to be

grasped concurrently with the first mentioned handle, substantially as set forth.

3. A gapped wheel comprising, a wheel having a radial gap provided with a transverse guideway at the periphery of the wheel, a patch fitted to slide in said guideway, dowel-pins projecting from opposite sides of said patch to the opposite walls of the guideway and adapted to enter dowel-holes in said walls, a spring co-operating with each dowel-pin and serving to seat it in its dowel-hole, and an inwardly projecting handle connected with each dowel-pin, substantially as set forth.

4. A gapped wheel comprising, a wheel having a radial gap provided with a transverse guideway at the periphery of the wheel at an angle to the axis of the wheel, a patch fitted to slide in said guideway, a dowel-pin projecting from said patch to a wall of the guideway and adapted to enter a dowel-hole in such wall, a spring co-operating with said dowel-pin and serving to seat it in its dowel-hole, and an inwardly projecting handle connected with the dowel-pin, substantially as set forth.

5. A gapped wheel comprising, a wheel formed with a rim and hub and connecting member between the rim and hub and having a radial gap provided with a transverse guideway at the rim, a patch fitted to slide in said guideway and complete the rim at the gap and having an inward projection at one side of said connecting member of the wheel, a dowel-pin projecting outwardly from said projection to a wall of the guideway and adapted to enter a dowel hole in such wall, a spring co-operating with said dowel-pin and serving to seat it in its dowel-hole, and an inwardly projecting handle connected with the dowel-pin, substantially as set forth.

FREDERICK WAGNER.
